CONTAINER CLOSURE WITH A TEAR STRIP OPENER

Lloyd G. Dunn, Richmond, Ind., assignor to Aluminum Company of America, Pittsburgh, Pa., a corporation of Pennsylvania

Filed Aug. 28, 1963, Ser. No. 76,379

Term of patent 14 years

(Cl. D58—26)

FIG. 2.

FIG. 1 is a top plan view of a container closure with a tear strip opener showing my new design; and

FIG. 2 is a sectional view taken on the line II—II of FIG. 1.

The dominant features of my new design reside in the annular tear strip with its one end U-curving inwardly to about the center of the closure and the linear embossments delineating the tear strip in the closure.

I claim:

The ornamental design for a container closure with a tear strip opener, substantially as shown and described.
